Assignee to

Lowell Manufacturing Company

Letters Patent No. 2451, Dated Sept. 25. 1866.

Design for a Carpet Pattern.

The Schedule referred to in these Letters Patent and making part of the same.

To all whom it may concern.

Be it known that Elmer J. Rey of Lowell in the County of Middlesex and State of Massachusetts have originated and designed a new Pattern for Carpets or other fabrics of which the following is a full, clear and exact description, reference being had to the accompanying drawings making part of this Specification.

This Design consists of two wide bands, running at right angles to each other, underlapping and overlapping each other, the particular combination is shown in the drawing.

The rest of the Design are the intervals of wreaths and little blocks. The colors employed for the different portions of the Design may be varied to suit the taste and wish of the manufacturer.

Claim.

What I claim as my invention and desire to secure by Letters Patent is The Design or Pattern for Carpets or other fabrics, herein set forth.
